UNITED STATES PATENT OFFICE.

JOHANN FEINENBURG, OF SOLINGEN, GERMANY

SCISSORS.

No. 891,238.

Specification of Letters Patent.

Patented June 23, 1908.

Application filed January 13, 1903. Serial No. 410,675.

To all whom it may concern:

Be it known that I, JOHANN FEINENBURG, a subject of the German Empire, residing at Solingen, in the Kingdom of Prussia, Germany, have invented a new and useful Improvement in Scissors, of which the following is a specification.

The subject of the present invention is a pair of scissors with interchangeable blades which are held in their relative positions by a pin working in an oblique slot, by a special bar and, in the usual manner, by the rivet or connecting pin. This is for the purpose of allowing the blades to be easily separated, as it is intended, by the present invention, to obviate the regrinding of large scissor blades and to replace them by others when they become blunt. In consequence, a considerable number of spare blades are sold with the scissors. In the case of the scissors for cutting the hair of brushes, bristles &c., one or both blades may be toothed or jagged.

Scissors with strong or large interchangeable blades, which are connected by screws and rivets, are well known, and it is intended to replace these by the present invention, as the interchangeability of the existing scissors is too cumbersome, and they do not lend themselves to the purposes described above.

The invention is shown in the accompanying drawing in Figures 1-5. Fig. 1 shows the scissors closed and Fig. 2 is a cross section in plan view. In Figs. 3 and 4 the connecting pin is loosened and the cutting blade is ready to be removed. Fig. 5 shows a further mode of construction in longitudinal section.

The parts *a* are provided with a bar *b* which may be attached in any suitable manner or may be made in one piece with the parts of the scissors. At the front or end there is a rivet, pin, bolt or other suitable object *c* which is suitably made larger at the head than at the bottom. There is, in the blades themselves, a hole *d* through which

passes the connecting bolt or pin *f* which holds the cutting blade firmly in position as soon as the scissors are closed. The cutting blade has an oblique slot *e* at the end which, at its top, is shaped to the form of the head of the pin *c*. When it is required to fasten 45 the scissors, the head of the pin *c* is inserted in the slot *e* and the parts of the scissors are pushed under the projecting edge 50 *b'* of the bar *b*; when the connecting pin *f* is pushed through the hole *d*.

The parts of the scissors may be slightly convex so that, by the curve, the blades are compelled to press firmly one against the other.

If desired, the bar *b* could be dispensed 60 with, and further rivets *g*, or other suitable means employed instead, as shown in Fig. 4. The bolt, pin, rivet *g*, or other similar contrivance, could be in the cutting blade and be inserted in holes in the other blade (Fig. 65 5). Also a pin or bolt could be used at the end near the connecting pin, to hold the cutting blade.

Having now fully described my invention, what I claim as new and desire to secure by 70 Letters Patent is:

1. Scissors provided with a pair of pivoted members, pins projecting therefrom, and cutting blades having oblique slots that are engaged by said pins, substantially as specified.

2. Scissors provided with a pair of perforated members, pins projecting therefrom, perforated cutting blades having oblique slots that are engaged by said pins, and a 80 pivot passing through the perforated members and blades, substantially as specified.

Signed by me at Dusseldorf, Germany this 27 day of Dec. 1907.

JOHANN FEINENBURG.
